UNITED STATES PATENT OFFICE.

SAMUEL H. BARTLETT AND HENRY E. WAITE, OF BRIDGEPORT, CONN.,
ASSIGNORS TO CHARLES F. LIVERMORE, OF NEW YORK, N. Y.

TELEPHONE-RECEIVER.

SPECIFICATION forming part of Letters Patent No. 253,812, dated February 14, 1882.

Application filed August 31, 1881. (No model.)

To all whom it may concern:

Be it known that we, SAMUEL H. BARTLETT and HENRY E. WAITE, both of Bridgeport, county of Fairfield, State of Connecticut, have 5 invented new and useful Improvements in Telephone-receivers, of which the following is a full, clear, and exact description, reference being had to the accompanying drawings, making part of this specification, in which—

10 Figure 1 represents a section through our improved receiver; and Fig. 2 is a face view of the same, with the ear-piece removed and the diaphragm or sounding-board partly broken away.

15 Our invention relates to an improvement upon what is known as the "Reiss receiver," or arrangement of magnet and armature upon the side of his transmitter constituting the sounder the armature of which vibrates as the 20 circuit is disturbed; and it consists in the combination, with the Reiss magnet and armature, of a diaphragm and ear-piece, through which the disturbances in the current are conveyed to the ear with greater distinctness, as herein- 25 after explained.

In the accompanying drawings, A represents a magnet, which may be similar to that of the Reiss, referred to; or, what is preferable, it may be in the form of a single-bar magnet, adapting it to be inclosed in a suitable handle, B, having an enlarged chambered end or head, B', surrounding the coil C and adapted to receive a diaphragm, D, and the ear-piece E, secured thereto in any suitable manner. The 30 handle part B of the body of the receiver has a cylindrical bore, b, through it, of uniform diameter, in which the magnet A rests for the greater part of its length, and above this, in the enlarged chambered head B', the bore or chamber is "stepped" or enlarged by successive annular rabbets or shoulders, the smaller chamber or portion thereof, b', adjacent to the handle part receiving the coil on the end of the magnet, the second and larger part b' receiving 35 the arm or armature a overhanging the end of the magnet, and the third or largest portion b³ receiving and supporting the diaphragm D, covering said armature and the end of the magnet.

40 The arm a is made of steel or other mag-

netic metal in the form of a thin flat spring, the end overhanging the magnet being provided with a small outwardly-projecting spur or point, a', which rests in contact with the disk or diaphragm D at or near its center, as 55 shown. The opposite or outer end of the arm a is rigidly secured to the rabbet or shoulder b² in such manner as, in its normal condition or state of rest, to support the inner end out of actual contact with the end of the magnet 60 A. In addition to this, the magnet itself is made longitudinally adjustable in the handle by means of a thumb or set screw in the handle end, adapting it to be set nearer to or farther from the arm a, as may be required for 65 securing the best possible results under the varying conditions of battery-power, &c.

The diaphragm or disk D may be of glass, mica, or other non-inductive material, being acted upon by the point a', under the retractive 70 power of the spring arm or armature a, said point a', as the arm is attracted to or repelled by the magnet, acting upon the diaphragm with which it is in contact. In order to secure the best results of this action the diaphragm 75 D may be cushioned upon rings of yielding material at d in such manner as to adapt it to be adjusted with the ear-piece E to or from the arm a, so as to make it bear with greater or less force upon the point a'; or the arm a itself 80 may be made adjustable toward and away from the diaphragm for the same purpose.

It is not essential that the diaphragm should be of non-magnetic substance—such as those named—as very good results have been obtained by the use of metal diaphragms; but the best results in practice have been obtained by the use of the material named, and these are therefore preferred.

The arrangement of the wires from the coil 90 and the binding-posts for connecting the line-wires therewith may be similar to such as are now in use, and they need not therefore be particularly described.

From the foregoing description, taken in 95 connection with the drawings, it will be seen that we employ the magnet and its armature, as shown in the apparatus of Reiss, referred to, in combination with a diaphragm and ear-piece so arranged that as the armature is re- 100

tracted, after being attracted by the magnet, it shall act upon the diaphragm, imparting the disturbances in the current thereto.

Having now described our invention, we claim—

In a telephone-receiver, the combination, with the bar-magnet, coil, and a diaphragm of non-magnetic material, of a spring-armature rigidly secured at one end and bearing at its other end against the diaphragm, said arma-

ture being disconnected from the magnet, but in inductive proximity thereto.

In testimony whereof we have hereunto set our hands this 30th day of August, A.D. 1881.

SAMUEL H. BARTLETT.

HENRY E. WAITE.
